UNITED STATES PATENT OFFICE.

ADOLF SCHWIEGER AND BENNO DOCTOR, OF HANOVER, GERMANY.

CIGAR-CUTTER.

1,025,542.

Specification of Letters Patent.

Patented May 7, 1912.

Application filed April 11, 1911. Serial No. 620,382.

To all whom it may concern:

Be it known that we, ADOLF SCHWIEGER and BENNO DOCTOR, subjects of the King of Prussia, residing at Hanover, in Germany, have invented certain new and useful Improvements in Cigar-Cutters, of which the following is a specification.

The object of this invention is to provide an improved device combining the functions 10 of a cigar-cutter and a fastener for a receptacle such as a cigar case, cigar box, match container or the like to which the cutter is attached, such device being adapted for attachment to the receptacle without any 15 material modification of the construction of the latter.

The invention is illustrated in the accompanying drawing, in which—

Figure 1 is a perspective elevation showing the cutter open, and Fig. 2 a similar view showing the cutter closed. Figs. 3, 4 and 5 show the cutter attached to a cigar case, open, partly closed and fully closed respectively. Fig. 6 shows the cutter attached to a cigar box. Fig. 7 shows the cutter provided with an adjunct adapted to serve as a holder for ash or for an ash-tray or the like.

Like reference letters designate like parts 30 throughout the drawing.

The device comprises two levers, marked *a* and *b* in the drawing, furnished with knife-edges *c* and *d* respectively, conforming to the circumferential shape of the cigar 35 near the pointed end. The lever *a* has a slot *e*, and a pin *f* fixed to the lever *b* is slidable in this slot.

The lever *a* is provided at its free end with a finger piece *n* by which the lever is 40 operated and having a lug *g* which serves as a catch to fasten the cover of a receptacle to which the cutter is attached.

It will be understood that if the perforated ends *h* and *i* of the levers are pivoted 45 to a fixed support, and the levers are in the position in which they are shown in Fig. 1, the tip of a cigar can be inserted between the knife-edges *c* and *d*, and be cut off by depressing the lever *a*, the cutter being by this 50 means folded, as shown in Fig. 2.

In the arrangement shown in Figs. 3, 4,

and 5, the cutter is pivoted at *m* and *l* to the inner face of one of the frame-members of the cigar-case A. The two frame-members are shut together, prior to the cutting of the 55 cigar, and by the act of cutting the catch *g* is made to engage the opposite frame-member, and fasten the case, as shown in Fig. 5.

Fig. 6 shows the cutter attached to a cigar box B provided, at the upper edge of 60 its front wall, with a saddle piece *k* forming a support to which the cutter is pivoted at *m* and *l*. This saddle-piece is fixed to the box by means of spikes formed at its 65 corners *o*.

The support *k* may be enlarged to afford space for advertising purposes, and may be provided, as shown in Fig. 7, with a hinged adjunct *x* which can be used as an ash-tray 70 or as a holder for an ash-tray or the like.

What we claim as our invention and desire to secure by Letters Patent of the United States is:—

1. A cigar cutter comprising a support, two levers having pivots spaced apart on 75 said support, disposed so that said levers can be rocked toward a position of parallel alinement between said pivots, said levers having substantially semicircular cutting edges disposed so that in an angular position of said levers in relation to each other said cutting edges form complementary parts of the circumference of a circular opening, and means engaging said levers with each other so that by the actuation of 80 one of them they can be collectively moved so that said circular opening is closed by the approach of the cutting edges toward each other.

2. The combination, with a receptacle 90 having a cover, of two levers having pivots spaced apart on said receptacle disposed so that said levers can be rocked toward a position of parallel alinement between said pivots, said levers having substantially semi-circular cutting edges disposed so that in an angular position of said levers in relation to each other said cutting edges form complementary parts of the circumference of a circular opening, means engaging said 95 levers with each other so that by the actuation of one of them they can be collectively 100

moved so that said circular opening is closed by the approach of the cutting edges toward each other, one of said levers being provided with a finger piece arranged to 5 serve as a catch to fasten the cover of said receptacle when the levers are in the position of parallel alinement.

In witness whereof we have signed this

specification in the presence of two witnesses.

ADOLF SCHWIEGER.
BENNO DOCTOR.
